UNITED STATES PATENT OFFICE.

PRINCE EDWARD WHITE, OF PERTH AMBOY, NEW JERSEY.

SHIP'S BERTH.

1,142,472.

Specification of Letters Patent.

Patented June 8, 1915.

Application filed May 9, 1914. Serial No. 837,483.

To all whom it may concern:

Be it known that I, PRINCE EDWARD WHITE, a subject of Great Britain, residing at Perth Amboy, 19 Fayette street, in the 5 county of Middlesex and State of New Jersey, have invented new and useful Improvements in Ships' Berths, of which the following is a specification.

The general object of this invention is to 10 reduce to a minimum on the part of a passenger on a ship, the disagreeable effects resulting from the rocking and pitching of the ship. And to these ends the invention consists of a berth, means for carrying the 15 berth in a non-rigid manner and a member for pivotally supporting the said means.

Other objects will appear and be better understood from that embodiment of my invention of which the following is a specification, reference being had to the accompanying drawings forming part hereof, in which;—

Figure 1 is a side elevational view of the device in operative position. Fig. 2 is an 25 end elevational view of Fig. 1. Fig. 3 is a side view of the device in the inoperative or folded position. Fig. 4 is a detail vertical sectional view taken on the line 4—4 in Fig. 2. Fig. 5 is a detail end view of a modified 30 form of cradle and means for supporting the same, and Fig. 6 is a perspective view of a modified form of supporting member.

As shown in the drawings the device is formed of the stand or supporting member 35 5, the carrying-beam 6 and the cradle or berth 7 which is carried by the beam.

The stand 5 is preferably formed of a pair of frames 8 and 9, which are hingedly secured at their upper ends to a crown or 40 cross-piece 10, thus forming a substantial shear, and for the purpose of strengthening or reinforcing, the cross-piece is provided with angularly disposed rabbets 11—11, which snugly receive the ends of the frames 45 as shown. It is quite obvious, that by virtue of the frames being disposed obliquely to the ground, the stand will have a tendency to spread apart, upon weight being applied thereto; and in order to retain the stand in 50 position, tie-rods 12—12 are provided at either side of the frame, and for the purposes of illustration the tie-rods are shown in the form of hooks.

The carrying-beam 6 is substantially 55 truss-shape in structure, and is formed of

two oblique-triangular shaped members having their shorter or homologous sides back to back as shown. These triangular members may be made of any suitable material, and for the purpose of being pivotally supported by the stand 5, the triangular members are provided with the hinges 13—13, which are suspended from a suitable hanger 14 mounted on the cap or cross-piece 10. The members are locked in the extended position by the latches 15—15, which are pivotally secured to one member and are adapted to engage with suitable studs 15'—15' provided on the opposing member as shown. It will be seen by referring to Fig. 2, that 65 the extreme or remote ends of the triangular members converge to substantial points, and upon these ends are mounted hooks 16—16, which carry the berth 7 by means of the chains 17—17; and for the purpose of reinforcing the remote ends of the beam, the ends are surrounded by suitable metallic bands or hoops 18—18 as shown.

The berth 7 may be provided with a suitable bedding and may be formed of any 70 suitable material, and is to be of such dimensions as to comfortably accommodate an occupant, and for this reason the berth is bellied out at the center as shown in Fig. 1. In structure the berth is formed of two substantially solid end pieces 19—19, which are appreciably semi-circular in shape, and are connected to each other by a series of spaced longitudinal laths or strips 20, which are bowed toward the center and are connected to each other by the semi-circular rib-bands 21, as shown; and for the purposes of reinforcing the berth the edges or upper longitudinal strips 20 are of greater size than the intervening laths.

In operation, the device may be positioned at any suitable location on a ship, such as the decks or the like, and the height of the stand need be only sufficient to suspend the berth clear of the floor or deck. As shown, the berth has universal movement, and as the ship pitches or rocks, the action will not affect the berth whatever, as the berth will seek its own center of gravity and remain relatively level. By referring to Figs. 1 and 100 3, it will be seen that the stand and the berth-carrying beam may be folded. The berth may be removed from its carrier, and by disengaging the latches of the carrying-beam and the tie rods of the stand, the two 105 110

latter members may be folded over on the hinged connections as shown in Fig. 3; thus the device may be stored away when inoperative, and obviously take up a relatively small space.

In the modified form of the invention, shown in Fig. 5, the chains 17 are dispensed with, and in lieu thereof, semi-circular yokes 22 are provided, which yokes are loosely secured at their center-portions to the ends of the carrying-beam 6. The berth is carried by the yokes by means of a series of spaced rollers 23, which are arranged in arcuate formation on the ends of the berth, and are adapted to be trained in position on the yokes as shown. Thus, as the ship rolls, the berth will travel back and forth on the yokes by means of the rollers, and obviously remain level.

In many cases, it may be desirable to have a permanent stand, and for this purpose, a rigid stand is provided as shown in Fig. 6. This stand is formed preferably of metal, and consists of the base or rectangular frame 24, which rigidly carries the arch 25, which is provided at its upper portion with

a depending bearing 26, for carrying the beam 6 and the berth.

It is obvious that those skilled in the art may vary the details of construction and arrangements of parts without departing from the spirit of my invention and therefore I do not wish to be limited to such features except as may be required by the claim.

30

35

What I claim as new is:

A foldable berth support comprising a cross piece, frames hingedly connected with the opposite sides thereof, hinge members pivotally connected with the intermediate part thereof and having angularly disposed end portions, beams fixed to the free end portions of the hinge members and adapted to abut against each other at their inner ends, and berth supports carried at the outer ends of the beams.

40

45

In testimony whereof I affix my signature in presence of two witnesses.

PRINCE EDWARD WHITE.

Witnesses:

MYRON MONTGOMERY,
BERNARD GOLDBERGER.
